GEORGE H. HARPER, OF TULSA, OKLAHOMA

COLLAR BUTTON

Application filed April 6, 1931. Serial No. 528,155.

The object of the invention is to provide a collar button of the conventional form with which is incorporated a means for engaging and retaining the tie of the user to prevent the knot of the latter dropping and exposing the button, as is frequently the case when the loop around the neck of the wearer is left loose enough for comfort; to provide a tie retaining means which, at the time of the insertion of the button through the button-holes in the neck band of the shirt and the collar band may be folded down out of the way and substantially positively held in such folded position, so that there may be no danger of its impinging on the fabric of the shirt or collar; and to provide a construction which may be included as an element of the conventional collar button without material increase in the expense of production 20 of the same.

With this object in view, the invention consists in a construction and combination of parts of which a preferred embodiment is illustrated in the accompanying drawings to 25 which, however, the invention is not to be restricted. The right is reserved to make such changes or alterations as practical use may dictate, in so far as such changes or alterations may be comprehended in spirit by 30 the annexed claims.

Figure 1 is a perspective view, partly in section, showing the invention applied in operative position.

Figure 2 is a front elevational view of the 35 structure of Figure 1.

Figure 3 is a view partly in elevation and partly in section of a collar button constructed in accordance with the invention.

Figure 4 is a front elevational view of the 40 invention showing the retainer in one of its folded positions, with the other or opposite folded position being indicated in dotted lines.

Figure 5 is a sectional view on the plane indicated by the line 5-5 of Figure 3.

The button in which the invention is shown as incorporated is of the conventional form having a base 10 with which is connected the centrally disposed shank 11, this shank carrying the pivotally mounted head 12 which

is of generally oval form with the pivot point, as indicated at 14, closer to one end than to the other so as to provide a bill portion 15 designed to be easily inserted through the button-holes in the collar band and collar 55 when the button is in use.

The head is of the usual hollow form and the pivotal mounting between it and the shank is of the conventional character which will yieldingly retain the head in either of its 60 two positions of alignment, with the shank or at right angles thereto.

The retainer constituting the invention consists of a hook 16 of U-shaped form, of 65 which one leg, as that indicated at 16^a is inserted into the head 12 through the edge of the bill 15 on the extremity of the latter, the other leg 16^b constituting a prong which may enter the knot 17 of the tie.

The hook 15 is susceptible of assuming several positions with reference to the bill of the head 12, the one where it curves around in front of the bill, as indicated in Figure 3, when it is in position to have the tie seated upon it, and the other two in the plane of the 70 bill on either side of the latter as shown in full lines and in dotted lines in Figure 4. In either of these two latter positions, the leg 16^b lies close to the edge of the bill, when its pointed extremity falls behind the shoulder 75 18 resulting from making the bill of reduced width. In this folded position of the hook, therefore, the prong or point is shielded by the shoulder 18 and the bill may be readily passed through the button-holes without 80 danger of the hook impinging on the goods.

To insure the hook retaining any one of its 85 adjusted positions, the upper end of the leg 16^a carries a cross-sectionally angular block 19 of which the sides bear against opposite 90 walls on the interior of the bill and in turning the hook to its operative position in front of the bill or into its folded position on either side edge of the latter, the corners are caused to bear against the interior walls of the bill, 95 slightly spreading the latter until the required angular or turning movement is effected, when the flat sides of the block again bear and the desired position of the hook secured. 100

The invention having been described, what is claimed as new and useful is:

1. A collar button having a head and a U-shaped hook of which one leg extends radially into the head through the edge thereof, the hook being angularly adjustable to dispose the other leg in parallelism with the head or in the plane of the latter.
2. A collar button having a head and a U-shaped hook of which one leg extends radially into the head through the edge thereof, the hook being angularly adjustable to dispose the other leg in parallelism with the head or in the plane of the latter, that leg interior to the head being provided with means for insuring the retention of the hook in any of its selected positions.
3. A collar button having a head terminating in a bill of reduced width as respects the head to provide a shoulder at the junction of the two, a U-shaped hook having one leg pivotally mounted in the bill at the terminal edge thereof to selectively dispose the other leg in overlapping relation to the bill in parallelism therewith or into folded relation at the side edge of the bill with its extremity behind said shoulder.
4. A collar button having a head terminating in a bill of reduced width as respects the head to provide a shoulder at the junction of the two, a U-shaped hook having one leg pivotally mounted in the bill at the terminal edge thereof to selectively dispose the other leg in overlapping relation to the bill in parallelism therewith or into folded relation at the side edge of the bill with its extremity behind said shoulder, the pivotally mounted leg being interior to the bill and terminally provided with a cross-sectionally angular block with its flat sides bearing against opposite interior walls of the bill.

In testimony whereof he affixes his signature.

GEORGE H. HARPER.
